UNITED STATES PATENT OFFICE.

ELMER McCLELLAN AFRICA, OF HUNTINGDON, PENNSYLVANIA, AND BARTHOLOMEW E. McSHEEHY, OF NUTLEY, NEW JERSEY, ASSIGNEES TO J. C. BLAIR COMPANY, OF HUNTINGDON, PENNSYLVANIA, A CORPORATION OF PENNSYLVANIA.

WRITING-TABLET.

1,241,694.

Specification of Letters Patent.

Patented Oct. 2, 1917.

Application filed January 18, 1908. Serial No. 411,445.

To all whom it may concern:

Be it known that we, ELMER McCLELLAN AFRICA, a citizen of the United States, and a resident of Huntingdon, in the county of 5 Huntingdon and State of Pennsylvania, and BARTHOLOMEW E. McSHEEHY, a citizen of the United States, and a resident of Nutley, in the county of Essex and State of New Jersey, have invented certain new and useful 10 Improvements in Writing-Tablets, of which the following is a specification.

This invention relates to certain improvements in tablets or pads of paper, and especially to such as are adapted to be used in 15 connection with papeteries, and the sheets of which are adapted to be folded to form double sheet note-paper.

According to our invention we form a tablet of sheets of paper of such dimensions 20 that when folded in the middle they form double sheet note-paper, whereby the sheets are kept together and whereby in writing the sheet written upon is held in place and the lower sheets form a support for those 25 above.

The tablet also preferably comprises a blotter attached thereto in such manner that it can be laid over the sheets.

An important feature of the invention is 30 the combination of a guide line sheet with the tablet. Preferably two such guide-line sheets are used. One is preferably of the same length and width as the unfolded sheets of the tablet, and the other is preferably of the same length and width as the folded sheet. Both of the guide line sheets are provided with lines running longitudinally of the tablet, and the large guide line sheet is preferably also provided with lines 35 running transversely. The transverse lines serve to indicate a margin when writing along the longitudinal guide lines, and also as transverse guide lines when it is desired to write transversely of the unfolded sheet 40 (from the top to bottom of the folded sheets) the full length thereof.

The guide line sheets are also preferably attached to the tablets in such manner that they may assume a proper position with relation to the sheet to be written upon, and in proper alignment without necessitating detaching of the sheet.

Any other design which it is desired to

have appear to the user through the sheet, may be contained on the guide sheet instead 55 of or in addition to the guide lines. In the preferred construction of our invention the full length guide sheet is adjusted beneath the letter sheet, so that after the first page is written upon the letter sheet may be unfolded or extended and the half sheet folded back out of the way, so that the second and third pages of the letter sheet are in position for use with the full length sheet beneath them. When the writing extends to 60 the last page, the letter sheet is again folded to its initial position over the half sheet and the latter with the letter sheet is turned back thus bringing into position the last 65 page of the letter sheet. 70

In the accompanying drawings wherein, we have illustrated several modifications of our invention,

Figure 1 is a perspective view of one form of a tablet attached for use in papeteries or 75 the like.

Fig. 2 is a plan of Fig. 1 showing the first page of the sheet in position for writing.

Fig. 3 is a similar view showing the second and third pages in position.

Fig. 4 is a similar view showing the last page in position.

Fig. 5 is a side elevation of Fig. 1.

Fig. 6 is an edge view or side elevation of the tablet of Fig. 1.

Fig. 7 is a perspective view of another modification.

Fig. 8 is a section on the line 8—8 in Fig. 7.

Fig. 9 is a perspective view of another 90 modification.

Fig. 10 is a plan view of our improved guide sheet.

Fig. 11 is a plan of the guide sheet of Fig. 9 detached.

Fig. 12 is a perspective view of another modification.

Fig. 13 is a perspective view, partly broken away, of a complete papeterie.

Referring first to Figs. 1 to 6, let A designate the tablet as a whole which is composed essentially of a number of sheets *a* connected along their upper edges at *b*. Preferably a back board *c* is provided as is common and a cover *d* which is connected 100 to the tablet at what may be termed its up- 105

per edge, or that edge at which the sheets are attached. Preferably the dimensions of the tablet are such that when the sheets are folded along the dotted line *e* (Fig. 1) the lower edge will meet the top edge, so that the paper assumes the proper form for correspondence, etc.

B indicates a guide sheet which is of substantially the same dimensions as the letter sheets of the tablet, and preferably such sheet is hinged to the tablet, by preference to the back board *c* as indicated in Fig. 6. The hinged joint may be formed in any suitable way, preferably by a strip of paper or canvas *f* (Fig. 6) which is glued to the back board *c* and to the under side of the guide sheet *B*. In this manner the lower edges of the letter sheets are left free. The hinge *f* is preferably stiff laterally, so that the guide sheet *B* tends to fold over in a substantially fixed plane, whereby it retains its position more effectively and does not move from side to side. When the guide sheet *B* is in position beneath one of the letter sheets (as shown in Fig. 3 for instance) it is held with sufficient firmness to prevent its displacement. Preferably when the guide sheet *B* is used to provide writing lines it is ruled with lengthwise lines *g* and transverse lines *h* so that the letter sheet may be written upon either longitudinally of the tablet or transversely thereof as desired. Preferably, as before stated, we also employ a second guide sheet *C* which is by preference about one-half the length of the tablet and is hinged to the latter at its top as shown in Figs. 1 to 6, or along the upper half of one of its sides as shown in Figs. 7 and 8. In the form shown in Figs. 1 to 6 it is hinged at the top by means of a strip *j* which is glued to the inside of the cover *d* as best shown in Figs. 5 and 6. The guide sheet *C* may be formed of two sections of paper with the strip *j* glued between them. Such sections are preferably connected so that they form in effect one part. It is ordinarily sufficient if the guide sheet *C* be ruled with a single set of lines *g'* extending longitudinally of the tablet, but it is important that such lines shall appear on both sides of the sheet.

In the use of the tablet of Fig. 1, when the sheet is to be folded to correspondence size the upper letter sheet is raised sufficiently to enable the guide sheet *B* to be folded down beneath it, whereupon the lower end of the letter sheet is folded over the guide sheet *C* so that its upper and lower edges coincide. During this action the edge *l* of the sheet *C* serves as a guide for folding the sheet. This brings the first page of the sheet in position for use, as indicated in Fig. 2, the guide *C* lying beneath such page and its lines being visible through the latter as indicated in dotted lines at *g'* in Fig. 2.

After the first page is written upon the letter sheet is extended to its full length bringing the second page into position over the lower part of the guide sheet *B*. The guide sheet *C* may be permitted to remain in its folded position, or, if the third page of the letter sheet is to be written upon also the sheet *C* will be folded upwardly over the cover as indicated in Fig. 3. When the fourth page of the sheet is also to be written upon the sheet *C*, with the letter sheet, is turned upwardly until it overlies the cover as indicated in Fig. 4, thus bringing the fourth page into position. In this position the rear side of the guide sheet *C* is brought into use with its guide lines appearing through the sheet as indicated in dotted lines at *g'*. When the sheets are in this position the cover forms a backing or support for the sheet. If the sheet is not to be folded to correspondence size, the guide sheet *B* is arranged beneath the top letter sheet and the latter written upon transversely, the crosswise guide lines on the sheet *B* being used.

In Figs. 7 and 8 the guide sheet *C'* is hinged to the back board of the tablet as best shown in Fig. 8 by a strip *m* glued to the guide sheet and to the under side of the back board. In use of this form of our invention the operation is the same as that indicated with reference to Figs. 1 to 6 except that for writing upon the last or fourth page of the letter sheet the guide sheet *C'* with the letter sheet is moved around its hinge until it lies along the back board of the tablet. The tablet may then be turned bodily around so that the writing of the last page is not upside down. Or the letter sheet may be detached from the top and adjusted upon the guide sheet so that the fourth sheet is in proper position.

In both of the modifications shown the guide sheet *B* may be folded between the bottom sheet of the tablet and its back board so that such sheet may be out of way when it is not desired to use it.

According to our invention, we prefer to form the guide sheets *B* and *C* (or *C'*) of blotting paper. By this means we are not only enabled to dispense with the use of a separate blotting sheet, but avoid any special manipulation of the paper or blotting means, the blotting operation being effected so to speak automatically. By reference to Figs. 1 to 6 it will be seen that after the first page of the letter is written upon and it is unfolded in the position of Fig. 3, the sheet *B* serves to blot the page. After sheets 2 and 3 are written upon and the sheet *C* is folded over along the upper half of the letter sheet, it serves to blot page 3 of such sheet. If page 2 is not already dry this is also blotted by the sheet *C* as it is turned over upon the upper side of such sheet, pre-

paratory to folding the combined guide sheet and paper into the position of Fig. 4. When the tablet is used without folding the paper the underside of the sheet B may be utilized for blotting purposes; it is especially adapted for this purpose, since its under side is not ruled. A separate blotting sheet n may however be provided as shown in Fig. 1 wherein it is attached to the underside of the cover. It will also be noted that one or more of the sheets B, C or C' may be unruled and used only as a blotter. It will also be observed that any design may be placed upon the guide sheets for drawing or other purposes. It is also obvious that many modifications may be made in the constructions shown and described without departing from the spirit of the invention. For instance, the guide sheet B may be hinged (in a manner hereinafter described for instance) to a side of the tablet instead of at its lower edge. Guide sheets may also be used of different sizes than those indicated.

In Fig. 9 we have shown a further modification of our invention in which the half length guide sheets C², instead of being hinged to the tablet is hinged to the guide sheet B, which latter is itself hinged to the lower edge of the tablet. In use the guide sheet B is inserted beneath the letter sheet, and the latter folded to half size as in the other constructions shown, with the guide sheet C² between its leaves. Pages two and three are written upon in the same manner as with the other constructions and page four is arranged in position by severing the letter sheet from the tablet and slipping it over the guide sheet C².

In Fig. 10 we have shown our improved guide sheet detached, such sheet being indicated by the reference letter B'. The provision of a guide sheet or combined guide sheet and blotter having guide lines arranged both longitudinally and transversely is of considerable importance either in tablets or in connection with loose sheets. By its use the writer can be guided when writing upon the paper in either direction. Moreover, such guide sheet can be furnished practically as cheaply as a sheet having lines extending in but one direction, since as the lines may be on one side of the sheet only, a single printing operation will suffice for the production of the lines.

In Fig. 11, we have illustrated a detached guide sheet, which may be of blotting paper if preferred and which has hinged to one of its sides the half length guide sheet C². Such combined guide sheets may be sold either in tablets, loose paper or the like or separately therefrom. It is susceptible of the same use as the combined guide sheets shown in Fig. 9.

In Fig. 12, we have shown still another modification in which the half length guide

sheet is omitted, the full length guide sheet B² being creased at its middle and its upper half being attached to the back board of the tablet as shown. The sheet B² is preferably ruled longitudinally on its back 70 and longitudinally and transversely on its front as shown. In the use of this construction the guide sheet B² is placed over the top sheet of the tablet and the letter is folded as before. This brings page one 75 of the letter sheet in position for use. After page one is written upon the letter sheet is raised and the guide sheet slipped beneath it, whereby pages two and three are brought into position for use. The guide sheet and 80 letter sheet are then moved about the hinge of the former, thereby detaching the letter sheet from the tablet, and the letter sheet is then arranged with its fourth page above the lower half of the guide sheet B², which 85 in this position is folded. A single guide sheet in this construction takes the place of the combined guide sheets of the other constructions shown.

In Fig. 13, we have shown a papeterie 90 comprising an appropriate box or package containing a plurality of envelops and a tablet constructed according to our invention, the tablet being of such size that its letter sheets when folded fit such envelops. 95 In combination with these features are two guide sheets which are preferably blotters, one a half length sheet and the other a full length sheet ruled transversely and longitudinally.

While we have shown and described several embodiments of our invention, such illustration and description are not to be understood as defining the limits thereof, as variations and modifications may be made 105 therein without departing from the spirit of the invention.

What we claim is:—

1. A tablet having a plurality of sheets of paper and having a guide sheet having 110 guiding provisions on a surface thereof, said guiding provisions being adapted to be visible through one of said sheets of paper, and said guide sheet being substantially half the length of said tablet, and means 115 for hinging said guide sheet to said tablet.

2. A tablet having a plurality of sheets of paper and having a guide sheet having guiding provisions on a surface thereof, said guiding provisions being adapted to be visible through one of said sheets of paper, and said guide sheet being substantially half the length of said tablet, and means for hinging said guide sheet to the binding edge 120 of said tablet.

3. A tablet having a plurality of sheets of paper and having a guide sheet having guiding lines on both of its surfaces, said guiding provisions being adapted to be visible through one of said sheets of paper, and 130
